UNITED STATES PATENT OFFICE.

FRANK H. HEITGER, OF INDIANAPOLIS, INDIANA, ASSIGNOR TO HEITGER CARBURETOR COMPANY, OF INDIANAPOLIS, INDIANA, A CORPORATION OF INDIANA.

CARBURETER.

1,132,934.

Specification of Letters Patent. Patented Mar. 23, 1915.

Application filed June 8, 1912. Serial No. 702,615.

To all whom it may concern:

Be it known that I, FRANK H. HEITGER, a citizen of the United States, residing at Indianapolis, Marion county, and State of Indiana, have invented and discovered certain new and useful Improvements in Carbureters, of which the following is a specification.

My said invention consists of certain improvements in the detail of construction and arrangement of parts of carbureters and it relates especially to the mechanism for controlling the feed of the gasolene, or other hydro-carbon fuel, whereby the supply may be automatically regulated to suit the requirements of the speed of the engine and conditions under which it is operating, all as will be hereinafter more fully described and claimed.

Referring to the accompanying drawings, which are made a part hereof and on which similar reference characters indicate similar parts; Figure 1 is a side elevation of a carbureter embodying my said invention; Fig. 2, a central vertical section through the same; Fig. 3 a detail showing portions of Fig. 2 on an enlarged scale; Fig. 4 a cross section on the dotted line 4—4; Fig. 5 a cross section on the dotted line 5—5, and Fig. 6 a cross section on the dotted line 6—6.

In said drawings, the portions marked A represent the mixing chamber, B the gasolene reservoir or float chamber, C an annular casing member or top interposed between said float chamber and said mixing chamber, and D the main air supply to the spray nozzle. These several parts are or may be of any common or approved construction, 40 that shown being the well-known Heitger carbureter, and therefore require no special description, except in so far as they relate to the particular features constituting my present invention.

The general structure and arrangement of the parts as well as the novel features involved therein, are more particularly described in my companion application No. 702,616. The valve 40 for controlling the auxiliary air inlet is mounted on a spring 41 as shown and described in my companion application No. 702,612.

The mixing chamber has a suction tube 10 depending therefrom on the lower end of 55 which is mounted by means of a screw-

threaded connection a casting 11, which embodies the connection with the air and gasolene supply, and the spray nozzle 12 is mounted thereon. Said spray nozzle has a conical seat for the needle valve 13 and said needle valve is formed with longitudinal grooves in its sides through which the gasolene is sprayed into the carbureting chamber, as is usual. Said needle valve 13 comprises a stem having a head 14 which is 60 mounted in a vertical chamber in a cylinder 16 which is formed with a screw-threaded shank 17 that screws through the aperture in casing A. The periphery of said cylinder 16 is formed with a ribbed surface with 70 which a spring detent 15 engages to prevent accidental turning. A screw cap 18 is mounted in the upper end of cylinder 16 adapted to limit the movement of head or piston 14 and said screw cap is also formed 75 with a periphery having notches or ribs with which another spring detent 19 engages, to prevent accidental turning. The upper end of the stem of the needle valve 13 is formed with a longitudinal bore ex- 80 tending to a point within the mixing chamber and transverse openings 20 lead radially therefrom into said mixing chamber.

In operation the needle valve is adjusted through the medium of the cylindrical head 85 16 to regulate the amount of gasolene that may be normally drawn through the grooves in the periphery of the stem through the spray nozzle. Upon the speed of the engine increasing to a point where the suction will be sufficient, the air pressure upon piston 14 through air vents 25 will operate to elevate said stem and needle valve 13 to the limit of the movement allowed by the adjustment of screw cap 18, so that a greater 90 95 quantity of gasolene will be allowed to pass through said spray nozzle. As the speed of the engine decreases, the weight of the stem will cause the stem to fall and the openings to be partially closed and the supply of gasolene thus automatically regulated to the quantity needed for the speed desired.

I claim—

1. A carbureter comprising a casing with carbureting and mixing chambers, a spray nozzle, a needle valve for controlling the flow of gasolene therethrough, a piston on the upper end of said needle valve, a chamber for said piston mounted to be vertically 105 110

adjusted in the casing, an adjustable cap for said chamber and a communication through a vertical bore in said needle valve between the mixing chamber and said 5 ton chamber, whereby said piston is adapted to be operated by the suction of the engine and both its normal and wide-open positions controlled, substantially as set forth.

2. A carbureter comprising a casing with 10 carbureting and mixing chambers, a spray nozzle, a needle valve for controlling the flow of gasoline through said spray nozzle, means for adjusting said needle valve to secure a normal opening of fixed area, 15 means for securing the part as adjusted, additional means for lifting said needle valve operated by the suction of the engine, means for limiting said lifting movement, and means for fixing the adjustment of said 20 limiting means, substantially as set forth.

3. A carbureter comprising a casing having carbureting and mixing chambers, means for regulating the feed of gasoline

consisting of a spray nozzle, a needle valve for regulating the openings through said 25 spray nozzle, a piston chamber adjustably secured in the casing, a piston connected with the stem of said needle valve and mounted in said piston chamber, the stem of said needle valve being formed with a perforation to establish communication from the mixing chamber to the piston chamber on one side of the piston and a vent being formed from said piston chamber on the opposite side of said piston, whereby the 30 feed of gasoline may be regulated automatically to conform to the speed of the engine, substantially as set forth.

In witness whereof, I have hereunto set my hand and seal at Indianapolis, Indiana, 40 this twenty-first day of May, A. D. nineteen hundred and twelve.

FRANK H. HEITGER. [L. S.]
